ATTORNEY

UNITED STATES PATENT OFFICE.

WILLIAM V. MALONE, OF JOPLIN, MISSOURI.

WATER HEATER.

Application filed May 11, 1927. Serial No. 190,555.

This invention relates to a water heater of that type adjunctive to and communicating with a water heating tank, boiler or steam boiler and the primary object thereof is to provide, in a manner as hereinafter set forth, a device of such character for expeditiously heating water and for maintaining a constant supply thereof at a minimum expense.

10 A further object of the invention is to provide, in a manner as hereinafter set forth, a water heater for communication with a water or steam boiler and with the heater constructed and arranged to provide for a fast circulation of water therethrough.

15 A further object of the invention is to provide, in a manner as hereinafter set forth, a water heater constructed and arranged to increase the heating surface thereof thereby expediting the water heating operation.

20 A further object of the invention is to provide, in a manner as hereinafter set forth, water heaters made as units to handle any size hot water job, as they may be attached to a tank direct or manifolded together to heat large tanks or may be manifolded together for heating hot water radiators or producing steam.

25 A further object of the invention is to provide, in a manner as hereinafter set forth a water heater having its heating element independent of that for the tank or boiler with which the heater is connected to and communicates with, and with the heater constructed and arranged whereby the heat therefor is conserved and which results in the operation of the heater with the greatest possible economy without loss by radiation.

30 A further object of the invention is to provide, in a manner as hereinafter set forth a water heater with two water chambers acting as two heaters in one and each provided with a hot water outlet, and to further provide the heater with a single cold water supply common to said chambers, whereby the displacement of hot water by the two outlets against the one inlet will cause a fast circulation of water through the heater.

35 Further objects of the invention are to provide, in a manner as hereinafter set forth, a water heater for the purpose referred to which is simple in its construction and arrangement, strong, durable, compact, thoroughly efficient in its use, conveniently in-

stalled with respect to a water or steam boiler, and comparatively inexpensive to manufacture.

40 With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications 45 can be resorted to which fall within the scope of the claims hereunto appended.

45 In the drawings wherein like reference characters denote corresponding parts throughout the several views:

50 Figure 1 is a top plan view of a water heater in accordance with this invention.

Figure 2 is a section on line 2-2 Figure 1.

Figure 3 is a section on line 3-3 Figure 1.

Figure 4 is a sectional plan of the heater. 55

Figure 5 is a vertical sectional view of the burner element.

Figure 6 is a section on line 6-6 Figure 5.

Figure 7 is an elevation of the closure plate for a clean-out opening. 60

65 A water heater, in accordance with this invention, comprises a body portion referred to generally by the reference character 8 and formed from a single casting. The body portion 8 includes an inner member 9 and an outer member 10 of greater length than the inner member 9, and the latter is suspended from the outer member 10, as well as being spaced therefrom. The inner member 9 preferably is of semi-oval cross section 70 and which forms an inner water heating chamber 11. The inner member 9 includes a top plate 12 which provides the top wall of the chamber 11. The plate 12 is of greater diameter than the remaining part of the inner member 9 whereby an outwardly directed flange 13 is formed at the top of the member 9. The diameter of the plate 12 is such with respect to the inner diameter of the outer member 10 to provide an endless, 75

narrow opening 14 between the edge of the flange 13 and the inner face of the member 10 at the top thereof. The opening 14 provides an air space or draft between the members 9 and 10 and which is provided to bring the flame of the burner, to be hereinafter referred to, up and around the member 9 and against the inner face of the member 10. 80

The member 10 is in the form of an annulus, which is hollow and provides an outer water heating chamber 15. The member 10 may be termed a water jacket which surrounds the member 9 and the latter is in the form of a bowl.

Interposed between the member 9 and inner wall of the chamber 15, in proximity to the upper ends thereof, is a pair of tubular members 16 which are diametrically disposed with respect to the members 9 and 10. The member 9 is formed with a pair of diametrically opposed openings 17 and the inner wall of the chamber 15 with a pair of diametrically opposed openings 18. The inner ends of the members 16 are integral with the member 9 and register with the opening 17. The outer ends of the members 16 are integral with the inner wall 29 of the chamber 15 and register with the openings 18. The tubular members 16, in connection with the openings 17 and 18 provide water circulating connections between the chambers 15 and 11. The members 16 further provide means for suspending the inner member 9 within and from the outer member 10.

Arranged between the members 9 and 10, in proximity to the bottoms thereof, is a tubular member 19 which inclines downwardly from the member 9 to the member 10. The member 9 is formed with an opening 20 and the inner wall of the chamber 15 with an opening 21. The tubular member 19 is formed integral with the members 9 and 10 and register with the openings 20, 21. The member 19 provides a clean-out connection for the chamber 11 and also assists in suspending the member 9 from the member 10.

The outer wall of the chamber 15 is formed with a pair of diametrically opposed circumferentially extending slots 23, 24, of substantial width and length and which provide clean-out openings for the chamber 15. The slot 24 opposes the opening 21 formed in the inner wall of the chamber 15. The slots 23, 24 are of rectangular contour and secured to the outer face of the outer wall of the chamber 15 and surrounding each of said slots is a rectangular frame 25 conforming in curvature to the curvature of the outer member 10. Each frame has anchored thereto and projecting outwardly therefrom a series of peripherally threaded members 26. Positioned against each frame 25, as well as connected thereto, in a manner to be presently referred to, is a closure plate 27 which conforms in curvature to the curvature of the member 10. The plate 27 as best shown in Figure 7, is of rectangular contour and formed with openings 28 in proximity to its top and bottom edges thereof and is further formed at each end with a pair of slots 29. The openings

28 and 29 are provided for the passage of the threaded members 26 and mounted on these latter are clamping nuts 30 which fixedly secure the plate 27 against the frame 25 thereby closing a slot 23 or 24. To provide for a water-tight joint, a packing 31 is interposed between the plate 27 and the frame 25.

The top plate, forming a part of the inner member 9, is formed with an opening 32 and integral with the upper face of the plate 12, is a vertically disposed interiorly threaded collar 33, having its inner diameter greater than the inner diameter of the opening 32 whereby the threaded inner face 80 of the collar 33 will be spaced from the opening 32, and an abutment or shoulder 34 will be formed at the inner end of the collar 33. Threadably engaging with the collar 33 is a hot water or steam outlet pipe 35. The plate 12 is furthermore provided with an opening 36 of greater diameter than the opening 32 and spaced a substantial distance therefrom, but in alignment therewith. Formed integral with the upper face of the plate 12 is a collar 37 of greater diameter than the collar 33 and which registers with the opening 36. The wall of the opening 36 is threaded, as well as the inner face of the collar 37 and engaging with said threads 95 is a removable clean-out plug 38.

The outer wall of the chamber 15 is provided with an opening 39, which opposes the opening 18 and said outer wall of said chamber 15 has formed integral with its outer face an interiorly threaded collar 40 which surrounds the opening 39 and the inner diameter of the collar 40 is greater than the diameter of the opening 39 thereby providing a shoulder or abutment 41. Threadably engaging with the collar 41 is hot water outlet pipe 42. The inner end of the pipe 35 is positioned against the shoulder or abutment 34 and the inner end of the pipe 42 is positioned against the shoulder or abutment 41. The pipe 35 provides a hot water or steam outlet for the chamber 11 and the pipe 42 provides a hot water or steam outlet for the chamber 15. The pipes 35 and 42 are disposed at right angles with respect to each other.

The outer wall of the chamber 15, is provided with an opening 43 which is arranged below the opening 39 and formed integral with the outer face of the outer wall of the chamber 15 is an interiorly threaded collar 44 having its inner diameter greater than the diameter of the opening 43 thereby providing a shoulder or abutment 45. Threadably engaging with the collar 44 and further positioned against the shoulder or abutment 45 is a cold water supply pipe 46. The opening 43 is positioned in proximity to the bottom of the chamber 15. The pipe 46 communicates with the water or steam 120 125 130

boiler in proximity to the bottom thereof. The pipe 42 communicates with the water or steam boiler at a level a substantial distance above the point of communication of 5 the pipe 46 with the water or steam boiler and the pipe 35 communicates with the water or steam boiler at a level a substantial distance above the point of communication between the pipe 42 and the water or steam 10 boiler.

The outer member 10 has formed with its bottom, at diametrically opposed points, a pair of depending short arms 47, to which is connected a pair of suspension members 15 48 for a valve controlled gas supply pipe 49 which extends through a block 50. The members 48 are fixedly secured to the block 50. The pipe 49 extends a substantial distance above the block 50 and carries a burner 20 element 51 and which is disposed in alignment with respect to the axis of the body portion 8.

The water heater when coupled up to a water or steam boiler expedites the heating 25 of water as well as the generating of steam, particularly in view of the fact that the water heater includes a pair of water heating chambers disposed to have large heating surfaces or areas for the flame from the 30 burner and the space formed between the inner and outer members of the body portion forms a heating space 52 disposed in a manner whereby the water heating chambers will be thoroughly heated, and the draft provided by the opening 14 will assist in providing 35 for the flame to attack the inner member 9 and inner face of the outer member 10 thereby rapidly heating the water within the water chambers, and under such conditions it is thought the many advantages 40 of a water heater, in accordance with this invention can be readily understood, and although the preferred embodiment of the invention is as illustrated and described, 45 yet it is to be understood that changes in the details of construction can be had which will fall within the scope of the invention as claimed.

What I claim is:

50 1. A water heater comprising a pair of water heating chambers, one surrounding and spaced from the other, circulating connections between said chambers, a water supply connection opening into the outer chamber, and an independent outlet connection for each of said chambers.

55 2. A water heater comprising a pair of water heating chambers, one surrounding and spaced from the other, circulating connections between said chambers, a water supply connection opening into the outer chamber, an independent outlet connection for each of said chambers, said outlet connections disposed at right angles with respect to each other.

3. A water heater comprising a pair of water heating chambers, one surrounding and spaced from the other, circulating connections between said chambers, a water supply connection opening into the outer 70 chamber, an independent outlet connection for each of said chambers, said outlet connections arranged above said supply connection.

4. A water heater comprising a bowl providing a water heating chamber, a hollow annulus surrounding and spaced from said bowl and providing a water heating chamber, circulating connections between said chambers and providing means for suspending 75 the bowl from the annulus, a supply connection for said chambers, and independent outlet connections for said chambers.

5. A water heater comprising a bowl providing a water heating chamber, a hollow 80 annulus surrounding and spaced from said bowl and providing a water heating chamber, circulating connections between said chambers and providing means for suspending 85 the bowl to the annulus, a supply connection for said chambers, and independent outlet connections for said chambers, said bowl having its top positioned in close proximity to the top of the inner face of the annulus to provide a narrow draft opening.

6. A water heater comprising a bowl providing a water heating chamber, a hollow annulus surrounding and spaced from said bowl and providing a water heating chamber, circulating connections between said chambers and providing means for suspending 100 the bowl from the annulus, a supply connection for said chambers, and independent outlet connections for said chambers, and said annulus having means depending therefrom for supporting a burner element below 105 said bowl.

7. A water heater comprising a bowl providing a water heating chamber, a hollow annulus surrounding and spaced from said bowl and providing a water heating chamber, circulating connections between said chambers and providing means for suspending 110 the bowl from the annulus, a supply connection for said chambers, and independent outlet connections for said chambers, said bowl having its top positioned in close proximity to the top of the inner face of the annulus to provide a narrow draft opening, and said annulus having means depending 115 therefrom for supporting a burner element below and axially of said bowl.

8. A water heater comprising a bowl providing a water heating chamber, a hollow annulus surrounding and spaced from said bowl and providing a water heating chamber, circulating connections between said chambers and providing means for suspending 120 the bowl from the annulus, supply and outlet connections for said chambers, and 125 130

clean-out connections for said outer chamber, said clean-out connections for said outer chamber being normally closed.

9. A water heater comprising a bowl providing a water heating chamber, a hollow annulus surrounding and spaced from said bowl and providing a water heating chamber, circulating connections between said chambers and providing means for suspending the bowl from the annulus, supply and outlet connections for said chambers, said bowl having its top positioned in close proximity to the top of the inner face of the annulus to provide a narrow draft opening, and normally closed clean-out connections for said outer chamber.

10. A water heater comprising a bowl providing a water heating chamber, a hollow annulus surrounding and spaced from said bowl and providing a water heating chamber, circulating connections between said chambers and providing means for suspending the bowl from the annulus, supply and outlet connections for said chambers, said annulus having means depending therefrom for supporting a burner element below said bowl, and normally closed clean-out connections for said outer chamber.

11. A water heater comprising an inner and an outer water heating chamber, one surrounding and spaced from the other, water circulating connections between said chambers, a single water supply connection opening into the outer chamber near the bottom thereof, an outlet connection for said inner chamber opening in the top of the latter, and an outlet connection for said outer chamber opening into such chamber near the top thereof.

12. A water heater comprising an inner and an outer water heating chamber, one surrounding and spaced from the other, water circulating connections between said chambers, a single water supply connection opening into the outer chamber near the bottom thereof, an outlet connection for said inner chamber opening in the top of the latter, an outlet connection for said outer chamber opening into such chamber near the top thereof, said outlet connections disposed at right angles with respect to each other.

13. A water heater comprising a body portion consisting of an inner and an outer member, each of said members being hollow and providing a water heating chamber, each of said members including a top, said outer member in the form of an annulus and surrounding said inner member and further depending below the same, said inner member having its top extending in close proximity to the inner face of said outer member to provide a circular, narrow draft opening, circulating connections between said inner and outer members near the upper portion thereof, an outlet connec-

tion for said inner member opening into the top thereof, an outlet connection for said outer member opening thereinto near the top thereof, and a supply connection opening into said outer member in proximity to the bottom thereof.

14. A water heater comprising a body portion consisting of an inner and an outer member, each of said members being hollow and providing a water heating chamber, each of said members including a top, said outer member in the form of an annulus and surrounding said inner member and further depending below the same, said inner member having its top extending in close proximity to the inner face of said outer member to provide a circular, narrow draft opening, circulating connections between said inner and outer members near the upper portion thereof, an outlet connection for said inner member opening into the top thereof, an outlet connection for said outer member opening thereinto near the top thereof, a supply connection opening into said outer member in proximity to the bottom thereof, said inner member being of semi-oval contour.

15. A water heater comprising a hollow bowl-shaped inner member providing a water heating chamber, an annular, hollow outer member surrounding and spaced from said inner member and providing an outer water heating chamber, the top of said inner member formed with a laterally extending flange having its edge positioned in close proximity to the inner face of the outer member to provide a narrow, circular draft opening, circulating connections between said chambers, means depending from the outer member for positioning a burner element below and axially of the inner member an outlet connection for each of said members, and a supply connection opening into said outer member.

16. A water heater comprising a hollow bowl-shaped inner member providing a water heating chamber, an annular, hollow outer member surrounding and spaced from said inner member and providing an outer water heating chamber, the top of said inner member formed with a laterally extending flange having its edge positioned in close proximity to the inner face of the outer member to provide a narrow, circular draft opening, circulating connections between said chambers, means depending from the outer member for positioning a burner element below and axially of the inner member, an outlet connection for each of said members, a supply connection opening into said outer member, said outlet connections disposed at right angles with respect to each other and said supply connection arranged below the outlet connection for said outer member.

17. A water heater comprising a hollow bowl-shaped inner member providing an inner water heating chamber, an annular, hollow outer member surrounding and spaced from the inner member and providing an outer water heating chamber, the upper end of the inner member positioned in close proximity to the upper end of the outer member to provide a narrow draft opening, 5 circulating connections between said chambers, a normally open clean-out connection

between said chambers, a normally closed clean-out means for said outer chamber and positioned near the bottom thereof, said circulating connections suspending the inner member from the outer member, an outlet connection for said inner chamber, an outlet connection for said outer chamber, and a supply connection for said outer chamber. 15

5 In testimony whereof, I affix my signature hereto.

WILLIAM V. MALONE.
